(57) **CLAIM**

The ornamental design for a combined hair trimmer with base, as shown and described.

DESCRIPTION

FIG. 1 is a front, right and top perspective view of a combined hair trimmer with base, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is an enlarged view of detail 10 in FIG. 2; and, FIG. 11 is another front, right and top perspective view of the combined hair trimmer with base, wherein the hair trimmer is settled in the base.

The broken lines depict portions of the combined hair trimmer with base that form no part of the claimed design. The dot-dash broken lines in FIGS. 1, 2, 9, and 10 depict the boundaries of the enlargements that form no part of the claimed design.
